UNITED STATES PATENT OFFICE.

FREDERIC W. STACK, OF NEW YORK, N. Y.

COIN-CARD.

No. 823,817.

Specification of Letters Patent.

Patented June 19, 1906.

Application filed April 12, 1905. Serial No. 265,184.

To all whom it may concern:

Be it known that I, FREDERIC W. STACK, a citizen of the United States, residing in the borough of Bronx, city, county, and State of New York, have invented an Improvement in Coin-Cards, of which the following is a specification:

My invention relates to coin-holders such as are used for sending coins safely through the mails.

The object of my invention is to provide a very simple, strong, and inexpensive device of the above-indicated character.

The invention will be fully described hereinafter and the features of novelty pointed out in the appended claim.

Reference is to be had to the accompanying drawings, in which—

Figure 1 is a face view of the blank from which my improved coin-holder is made. Fig. 2 is a plan of the completed article, and Fig. 3 is a section on line 3-3 of Fig. 2.

I form my improved coin-holder from a rectangular piece of cardboard or like material, which is divided into two unequal parts A and B by a line of scoring C parallel with the shorter sides of the rectangle. The smaller part A is adapted to be folded over upon the larger part B, as shown in Figs. 2 and 3, and to be secured by means of paste or other adhesive holding the three edges of the smaller part or flap A. The pocket thus formed is given the proper size or depth by embossing a circular or approximately circular portion D on the flap A, as shown, adjacent to a slot E, which is parallel with the short or transverse side of the holder. The embossed portion D extends to the central portion of the slot E,

which, however, extends to both sides beyond the entrance to the approximately circular pocket. This relative arrangement of the embossed portion and of the slot properly centers and guides a coin during its insertion into the pocket from the slot E and at the same time allows the holder to be used with equal efficiency for coins of various sizes. The embossed portion yields somewhat as the coin is forced in, and as soon as the coin passes the edge portion F the elasticity of said portion will cause the coin to be snapped against the backing formed by the part B, and said edge portion or edge strip F will then form a stop to prevent the withdrawal of the coin. The coin is effectually concealed and protected against detection or loss in transit. The recipient destroys the holder by cutting it preferably at the slot E, and thus releases the coin.

I claim—

A coin-holder, comprising a piece of stiff material doubled for a portion of its length and provided in one of the layers of the doubled portion with a transverse slot for the insertion of a coin and an approximately circular embossed pocket-forming part which connects with said slot for a distance smaller than the length of the slot, the ends of the slot extending beyond the said embossed part.

In testimony whereof I have hereunto set my hand in the presence of two subscribing witnesses.

FREDERIC W. STACK.
